INVENTOR,

Hanson E. Waddell
by George H. Christy, ACPY.

UNITED STATES PATENT OFFICE.

HANSON E. WADDELL, OF WHEELING, WEST VIRGINIA.

DESIGN FOR THE SURFACE ORNAMENTATION OF DISHES.

SPECIFICATION forming part of Design No. 19,749, dated April 1, 1890.

Application filed October 30, 1889, Serial No. 328,713. Term of patent 7 years.

To all whom it may concern:

Be it known that I, HANSON E. WADDELL, a citizen of the United States, residing at Wheeling, in the county of Ohio and State of West Virginia, have invented or discovered a certain new and original Design for the Surface Ornamentation of Dishes, of which the following is a specification.

The invention described herein relates to a certain new and original design for surface ornamentation of dishes.

In the accompanying drawings, forming a part of this specification, Figure 1 is an under side plan view of a celery-dish embodying my design. Fig. 2 is a similar view of a circular dish having the same ornamentation; and Figs. 3 and 4 are sectional views on the lines *x x* and *y y*, respectively, of Fig. 2.

The shape or contour of the dish or vessel in which my novel ornamentation is embodied is immaterial—as, for example, in Fig. 1 is shown an oblong dish and in Fig. 2 a circular dish, each having similar ornamentation; but the interior surface is plain—that is, flat or of regular or unbroken curvature.

The characteristic features of the design consist of a series of ribs 1, which commence

at the edge of the dish, extend downward, forming its sides, and as they go downward curve or sweep off laterally to one side, and so pass the bottom center of the dish. Of course as they do this they approach each other, and to a greater or less extent unite along a common line or narrow area of junction; also it will be seen that they grow narrower as they approach each other, and some of the narrowing points or ends merge into each other, while others sweep across into what may be considered as a handle or finger-piece 2. The ribs 1 and 2 are oval, or substantially so, at their ends or points, have curved outer faces 3 for portions of their length, as shown in Fig. 4, and then merge into a V shape in cross-section, as at 4.

I claim herein as my invention—

The design for the surface ornamentation of dishes, substantially as shown and described.

In testimony whereof I have hereunto set my hand.

HANSON E. WADDELL.
